UNITED STATES PATENT OFFICE.

WALTER D. DAVIES, OF BROOKLYN, NEW YORK, ASSIGNOR TO THE ANSONIA CLOCK COMPANY, OF ANSONIA, CONNECTICUT.

DESIGN FOR A CLOCK-CASE.

SPECIFICATION forming part of Design No. 14,892, dated November 6, 1883.

Application filed August 27, 1883. Term of patent 7 years.

To all whom it may concern:

Be it known that I, WALTER D. DAVIES, of Brooklyn, in the county of Kings and State of New York, have originated and produced 5 a new Design for Clock-Cases, of which the following is a specification.

My design for a clock-case consists in the representation of a bale or bag of merchandise, having the dial of the clock on one of its 10 sides.

The design also consists in the representation of a bale or bag having bands extending horizontally and vertically upon it, and having a dial-plate on its side.

15 The accompanying drawing is a perspective view of a clock embodying my design.

A designates the representation of a bale or bag of merchandise, which forms the clock-case. It is crossed horizontally and vertically 20 by bands *a*, and on the side is a dial-plate, B,

which has the appearance of covering the bands at their intersection. The dial-plate B bears upon it the dial B', and C designates the hands of the clock.

What I claim, and desire to secure by Letters Patent, is—

1. The design for a clock-case, consisting in the representation of a bale or bag having the dial of the clock on one of its sides, substantially as shown and described. 25

2. The design for a clock-case, consisting in the representation of a bale or bag having bands extending horizontally and vertically upon it, and having a dial-plate on its side, substantially as shown and described. 30

WALTER D. DAVIES.
